(57) CLAIM

The ornamental design for a retractable utensil device, as shown and described.

DESCRIPTION

FIG. 1 is a perspective view of a retractable utensil device design;

FIG. 2 is the front view of the design shown in FIG. 1; FIG. 3 is the rear view of the design shown in FIG. 1; FIG. 4 is a left side view of the design shown in FIG. 1; FIG. 5 is a right side view of the design shown in FIG. 1; FIG. 6 is a top view of the design shown in FIG. 1; and, FIG. 7 is a bottom view of the design shown in FIG. 1.

The broken line showing of a cigarette lighter in FIG. 1 is for illustrative purposes only and forms no part of the claimed design.
